REFRIGERATOR CONSTRUCTION

Robert H. Bishop, Champaign, Ill.

Application June 14, 1945, Serial No. 599,413

1 Claim. (Cl. 220—9)

1

This invention relates to an improved insulated cabinet construction and particularly to a cabinet used in refrigeration.

One of the objects of the present invention is to provide a cabinet construction having hermetically sealed insulation.

Another object of the invention is to provide an apparatus which will form an effective seal around the door and the door opening in the cabinet when the door is closed.

Another object of the invention is to provide a cushion and seal which also acts as a decoration.

Another object of the invention is to combine the stiffening means for the walls of the cabinet with the container means for containing the insulation between the walls.

A further object of the invention is to provide a structure which minimizes the vapor flow of moisture from the exterior to the interior of the cabinet.

Still another object of the invention is to provide a breaker strip or joint between the inner and outer side walls of the cabinet in such a manner as to prevent transmission of heat therethrough.

An important object of the invention is to provide a wall construction and seal around the lid which is easy and economical to build and which can be rapidly assembled.

In cabinet, and especially refrigerator cabinet construction, it is necessary to have breaker strips which not only serve to support and space apart the side walls containing the insulation, but are also used around the door jamb to provide a sealing area between the door and cabinet. Most of the designs are directed towards preventing heat losses from the metal side walls through the breaker strip and for that reason complicated construction has been used in the past which is difficult to build and is expensive in construction.

Furthermore most of the prior devices have not proved satisfactory for preventing heat from passing from the exterior of the box through the side walls by way of the breaker strip to the interior of the box. Such prior devices have not been found satisfactory for sealing in the insulation contained between the side walls of the cabinet which is highly desirable for obtaining an efficient refrigerator cabinet.

These difficulties have been overcome by the construction described herein and my invention has the following advantages.

The breaker strip which is continuously attached, for example by welding, throughout its length provides for hermetically sealing the in-

2

sulation between the metal sides or sheets forming the side walls of the cabinet. Insulation not so sealed either tends to take up moisture which makes it less efficient or it tends to dry out causing shrinking of the insulation and permitting the insulation to settle to the bottom leaving no insulation at the top.

Welding of the breaker strip is a cheap and economical way to attach the breaker strip to the two metal sheets forming the wall of the cabinet. Previously this has not been extensively used since it was difficult to hide and it must be hidden for the sake of appearance. Refrigerators, display cabinets, food freezing units and the like must have a certain amount of "eye-appeal" in order that they may be sold. By use of my construction I am able to use welding and such welds are covered by a rubber-like seal and the rubber-like seal itself, by extending over the outside edges of the walls, adds a decorative feature to the overall appearance of the cabinet.

My construction provides a cushion around the door opening for cushioning the closing of the lid or door and such cushioning provides a total length seal around the entire perimeter between the door and the cabinet door opening.

Two of the big problems in refrigerator construction are (1) preventing heat from the exterior from being transmitted to the interior and (2) preventing transfer of moisture in the form of vapor through the walls from the exterior to the interior.

In regard to (1) this problem would be very easy if it were not necessary to space apart and support the sheets forming the side walls for receiving insulation between the sheets. Such insulation of course must be provided. However the sheets forming the walls must be supported and various breaker strips for this purpose have been used in the past with but a single thought in mind, i. e. preventing heat transfer by way of the breaker strip. Metallic breaker strips and the like have been used in order to provide strength and various means have been used to retain their advantage as a support and to offset their heat transfer properties, which is a disadvantage, by insulating them from the side sheets with cements, plastic materials, insulating materials and the like. However as the walls expanded and contracted due to changes in temperature such heat insulators would gradually pull apart from the sheets forming the walls and from the breaker strip, allowing a flow of vapor or moisture to pass through the side walls to the interior of the box. This had two bad effects: (a)

it caused undue condensation on the refrigerator coil in the box resulting in an uneconomical operation as well as making the cooling coil less effective, (b) it permitted the insulation to become water soaked and when the insulation froze it crumbled and greatly reduced its efficiency.

In my construction I sacrifice to a very limited extent the prevention of heat transfer through the breaker strip and provide a means for absolutely preventing a flow of vapor from the exterior to the interior by hermetically sealing in the insulation so moisture can never get to it and by providing a total length cushion seal around the lid and lid opening.

In general this invention comprises a cabinet having an opening and a door for closing the opening. The walls are constructed by welding a breaker strip to the inner and outer metal sheets comprising the wall in such a manner as to form a recess between the metal sheets adjacent the door opening. The weld must be uniform and continuous in order to seal in the insulation contained between the metal sheets. The recess formed by the breaker strip is filled with a cushion-like material and is extended slightly above the edges of the metal sheets to provide a cushioning effect when the lid is closed. The cushioning material may be cork, fibrous wood, spongy sheet material, cardboard, sponge rubber, insulating blocks and the like as long as such material has some resiliency to provide a cushioning effect and at the same time does not tend to crumble or break under repeated closing of the door.

The breaker strip is made as thin as possible in order to transfer as little heat as possible. Furthermore a U-shaped breaker strip provides a longer path of travel of heat therethrough.

Especially is there less heat loss in my device because the U-shaped breaker strip rests directly on insulation and the large mass of insulation conducts heat away before it can reach the inside of the box. The cork like material in the recess of the breaker strip acts in the same manner. I therefore minimize the flow of heat through the breaker strip by (1) longer path of travel, (2) using light gage metal and (3) having the breaker strip in direct contact with insulation and the like to take away the heat by conduction. This is obtained while still retaining the feature as substantially preventing all "vapor flow" through the walls of the box or through the seal around the door or lid.

In order to hide the welding and the portion of the breaker strip construction which tends to lessen the "eye appeal" characteristics of the cabinet, the cushioning material may extend over the edges of the metal sheets forming the wall in order to hide all of the welding and may be designed so that it also provides a decorative feature. However it is usually preferred to place over the cushioning material placed in the recess, a rubber-like material which covers the cushioning material and the welded breaker strip and is preferably extended over the edges of the metal sheets. It can provide a decorative feature by having the portion of the rubber-like material, which extends over the metal sheets forming the outside of the box, corrugated, or other designs may be used. Such cover material may be rubber, plastic film, molded plastic and similar materials but materials somewhat resilient are preferred.

It is preferred to use a U-shaped breaker strip for two additional reasons than those given above.

(1) The sides of the U can readily be welded to the metal sides of the wall.

(2) The U-shaped breaker strip provides a recess into which can be placed the cushion material as above described.

Other advantages, uses and objects will be apparent by referring to the drawings which show a perspective view of a cross-section of a portion of a cabinet wall and door or lid. The lid section 10 is generally designated by A and the wall construction by B, the two sections coming together when the lid is closed along the line C—C. The interior of the box is denoted generally as D.

Referring to side wall construction B, metal side walls or sheets 1 are spaced apart and fastened together by a U-shaped breaker strip or joint 2 which is welded at 3. The U-shaped breaker strip should be made of as light gauge material as possible. Preferably the sheets 1 are 20 gauge and the breaker strip is 30 gauge. A continuous and uniform weld seals the insulation between the walls and thereby the insulation is unaffected by exterior atmospheric conditions and primarily it prevents a "vapor-flow" through the walls from the exterior to the interior.

Prior to inserting the U-shaped breaker strip 2 between the walls, insulating material 6 is placed in a preformed corrugated box 7 and the packaged insulation is placed between the sheets 1. The corrugated box not only serves to contain the insulation but also acts as a stiffening means for the side walls 1. It is easier to provide a suitable means for joining the side walls to the floor of the box, for example, than it is to provide a breaker strip adjacent the door jamb. It is of course necessary to have the insulation hermetically sealed between the walls of the remaining portion of the cabinet not shown in the drawing, in order to accomplish the objects of my invention and in general the same type breaker strip is used.

The outer portion 8 of the wall 1 may be finished with paint, porcelain or any other suitable material which is durable and has a good appearance.

As shown on the drawing, it is preferable to have the U-shaped breaker strip inserted between the plates 1 to form a recess and to have the upper edges of the strip welded at 3 substantially flush with the upper edges of the metal sheets 1. The weld must be uniform and continuous. In the recess a resilient material 4 is inserted to provide for proper cushioning upon closing of the lid. The particular type of resilient material is not important but it is preferable to have a porous, non-crumbly material like cork although fibrous wall board, sponge rubber, and other materials may be used. The cushioning material 4 should extend somewhat above the edges of the plates 1 as shown in order to provide the proper cushioning effect and it necessarily follows that it must be durable enough so it will not break or crumble during repeated opening and closing of the door or lid A.

A sealing cover comprising a rubber-like material 5 is placed over the cushion material 4 and extends over the sides in order to completely hide the welded joint between the U-shaped breaker strip and the side walls. This sealing cover may be rubber, plastic or other material of a similar nature but should be in itself somewhat resilient to supplement the cushioning effect of the cork-like material 4. The sealing cover 5 may be of a decorative design on the outside of

the cabinet such as the corrugations shown in order to serve both a useful and an ornamental function.

The lid or door A of the cabinet is similarly constructed. The lid in general comprises metal sheets 9 enclosing insulation 6 in corrugated cardboard 7. The outer sheet 9 is curved as shown for the sake of appearances and may be finished at 8 by paint, porcelain and the like.

A stiffening member 10 is provided at the corner to make a strongly constructed lid, and is welded to outer sheet 9 at 11. The inside sheet 9 is bent to form leg 12. A U-shaped member 13, similar to breaker strip 2 is placed between leg 12 and member 10 and welded at 11 and 14. This weld must be continuous throughout in order to seal in the insulation and prevent the "vapor-flow" as previously discussed. The U-shaped member 13 supports part of insulation 6. Again in the lid construction hermetically sealed insulation preventing "vapor-flow" is obtained and yet heat loss through the breaker strip is kept at an absolute minimum.

Cork-like material 4 and a rubber cover 5 are provided in a manner similar to the wall construction.

Thus when the door is closed, a tight seal is formed between the rubber covers 5 preventing any loss of heat from the interior of the box to the outside and the entire structure forms a cushion which is important in frequent closing of the lid to prevent jarring which is not only discomforting to those using the cabinet but is also detrimental and sets up strains and stresses in the remaining structure.

I claim as my invention:

In a receptacle having insulated walls and a door, a wall construction comprising a pair of spaced metal plates terminating in free edges in a common plane, insulating material between said plates, a sheet metal breaker strip of

U-shape in cross-section having its legs secured in sealing engagement to said plates with the ends of said legs substantially flush with said free edges of said plates and hermetically sealing the space between said plates, the portion of said breaker strip which connects the legs being spaced inwardly from the free edges of such plates to form a recess between the edges of said plates, resilient insulating material disposed in said recess and projecting beyond the free edges of said plates to form a cushion for the door of the receptacle, and a resilient, elastic, generally U-shaped cushion covering disposed over said resilient insulating material and over the edges of said plates to conceal said resilient insulating material and the free edges of said plates, said elastic U-shaped cushion covering forming the abutting surface for the door.
